[57] CLAIM

The ornamental design for a trailer hitch alignment mirror,
as shown and described.

DESCRIPTION

FIG. 1 is a front elevation view of a trailer hitch alignment mirror showing a first embodiment of my new design.

FIG. 2 is a rear elevation view thereof.

FIG. 3 is a left side elevation view thereof, the right side
being a mirror image thereof.

FIG. 4 is a top plan view thereof.

FIG. 5 is a bottom plan view thereof.

FIG. 6 is a front elevation view of a trailer hitch alignment mirror showing a second embodiment of my new design.

FIG. 7 is a rear elevation view thereof.

FIG. 8 is a top plan view thereof.

FIG. 9 is a bottom plan view thereof.

FIG. 10 is a right side elevation view thereof, the left side
being a mirror image thereof.

FIG. 11 is a right side elevation view of the first embodiment
of the trailer hitch alignment mirror as it is mounted on a
trailer tongue for use in providing to the vehicle operator a
view of the trailer hitch coupling process; and,

FIG. 12 is a right side elevation view of the second embodiment
of the trailer hitch alignment mirror as it is mounted on a
towing vehicle for use in providing to the vehicle operator
a view of the trailer hitch coupling process.
